PALLET FOR STAMPING MACHINES

Henry A. Mintz, Norwood, Mass.

Application August 30, 1947, Serial No. 771,483

2 Claims. (Cl. 101—391)

1

This invention relates to stamping machines, and more particularly to such machines for branding gold letters into the surface of articles made of leather or other material.

One of the objects of this invention is to provide a novel, simple and effective arrangement for supporting and centering a line of type on the pallet of such a machine.

A further object is to devise such an arrangement wherein the centering of said line of type is accomplished automatically without the necessity for the exercise of judgment on the part of the operator.

The foregoing and other objects of this invention will be best understood from the following description of an exemplification thereof, reference being had to the accompanying drawings wherein:

Fig. 1 is a side elevation of one form of the novel stamping machine;

Fig. 2 is a front view of the pallet shown in the machine of Fig. 1;

Fig. 3 is a bottom view of said pallet; and

Fig. 4 is a top view of the base plate of the machine shown in Fig. 1.

The machine illustrated is of the type intended to brand identifying marks on leather articles, and includes a base 1 upon which are formed bosses 2 between which is rotatably mounted a shaft 3. The shaft 3 is carried by pins 4 received in corresponding bores in the bosses 2. The shaft 3 carries an arm 5 which has formed thereon a branch arm 6 which carries a pallet 7 rigidly secured thereto. The arm 5 is extended to form a handle 8, whereby the entire arm assembly carrying with it the pallet 7 may be rotated about the pins 4. In order to receive the article 9 to be stamped, base 1 is provided with a pair of spring arms 10 under which the edges of the article to be stamped can be slipped, and thus be held firmly to receive the impression from the type carried by the pallet 7. The spring arms 10 can be retained by some suitable means, such as screws 11. The base plate 1 may be provided with screw-holes 12, whereby the machine may be secured in place by suitable fastening means, such as screws.

The pallet 7 consists of a type-holding block 13 rigidly secured to the outer end of arm 6. The block 13 is formed with a front face 14 and an upper extension 15 having a lower surface 16. Type 17 in any desired arrangement may be assembled in the block 13 on surfaces 14 and 16. In order to retain the type 17 in place, a clamping bar 18 is used to clamp the type onto surface 16.

2

The opposite ends of the bar 18 are carried by a pair of stiff support wires 19, the back ends of which are rotatably supported in a pair of plates 20 secured by means of screws 21 to the front edge of the extension 15 on the block 13. In this way the bar 18 may be swung away from the face 16 when it is desired to rearrange the type 17. The bar 18 is forced down into clamping engagement with the type 17 by means of a clamping screw 22 threaded through a plate 23 formed on the front end of an overhanging arm 24. The arm 24 is formed on the upper portion of the block 13, and is located centrally thereof. The outer end of the screw 22 is formed with a suitable head 25 so that its inner end 26 may be forced down against a flattened portion 27 on the bar 18. It will be noted that the bar 18 has the shape of a prism, preferably square, so as to provide a linear edge 28 which bears against the line of type 17. The resulting line of contact between the type 17 and the bar 18 affords ample clamping against the surface 14, but permits the type to slide in a direction parallel with said line of contact when a moderate amount of pressure in that direction is exerted upon the type. However, motion of the type in a direction at right angles to said line of contact is considerably more difficult. Thus, when the type 17 is assembled on the surfaces 14 and 16 and clamped by the bar 18, the type is effectively held against said surfaces, but motion parallel to said surfaces can be produced to center the type on the block 13.

Centering means for the type 17 is provided by a pair of centering blocks 29 mounted to slide along the top and front faces of the block 13 and caused to move simultaneously in opposite directions by means of a lead screw 30 supported by and rotatably mounted in the plates 20. The screw 30 is provided with one thread 32 threaded through the upper end of one block 29 and another thread 33, cut in the opposite sense to the thread 32, and threaded through the upper end of the other block 29. One end of the lead screw 30 projects beyond one block 20, and is provided with a suitable knob 34 in order to rotate the lead screw. As said knob 34 is rotated, the centering blocks will be moved simultaneously in opposite directions and to the same degree. The device is assembled so that the space between the inner surfaces of the block 29 is always centered on the machine. The type 17 is adapted to be clamped between these inner surfaces. Thus when the knob 34 is rotated to move the blocks 29 toward each other, said blocks will

clamp the type 17 between them, and thus will automatically center the type in the machine.

The arrangement described above affords a particularly simple arrangement for the removal, insertion and centering of type. In order to arrange the type, the operator grasps the handle 8 and rotates the arm 5 carrying with it the pallet 7 so that the bottom of the block 13 faces the operator, presenting the appearance shown substantially in Fig. 3. The knob 34 is rotated to separate the blocks 29 and the clamping screw 22 loosened to permit the bar 18 to swing away from the type 17. The previous line of type may be removed and the new type assembled on the faces 14 and 16. Then the head 25 is turned to force the bar 18 down against the line of type. No particular care need be exercised in order to center the type, but usually the bar 18 is not clamped as tightly as it can be to permit the subsequent centering action to occur more freely. Thereupon the knob 34 is rotated to cause the blocks 29 to approach each other. If the type 17 is not in the center, one or the other of the blocks 29 will push the line of type to its centered position where both blocks 29 will clamp the line of type and thus close up any spaces which may have been left when the operator placed it in the machine. It will be remembered that all such centering and clamping motion is permitted by the shape and arrangement of the bar 18 which nevertheless effectively prevents any motion of the type away from the surfaces 14 and 16. Thereupon, the head 25 may be given an additional twist to increase the clamping force of the bar 18 to its final value. When so assembled and centered, the type may be impressed on the work 9.

Before operating on the work in devices of the kind herein involved, it is usually desirable to heat the type to a relatively high temperature in order to secure the proper transfer of the gold leaf, or other printing material, to the article to be stamped. For this purpose the block 13 carries an electrical heating element 35, shown diagrammatically by dotted lines in Fig. 3. In order to support the heating element to produce a maximum of heating efficiency, the block 13 is provided directly to the rear of surface 14 with a bore 36 extending substantially along the entire length thereof. The heating element 35 is received within the bore 36 and carries at one end thereof a plug 37, carrying contacts 38, whereby an electrical connection may be made to the heating element 35.

Of course it is to be understood that this invention is not limited to the particular details of the arrangement as described above as many equivalents will suggest themselves to those skilled in the art.

What is claimed is:

1. A pallet for a stamping machine comprising a block adapted to support a line of type, said block having an elongated surface upon which the type is to be assembled and a surface

extending at right angles from one edge of said elongated surface and upon which the end of said type is to rest, said pallet being open on the two sides facing said surfaces whereby said surfaces are freely accessible for the assembly of said type, an elongated clamping bar having the shape of a prism and having a clamping edge lying along a corner edge of said prism, said clamping edge being adapted to provide a substantially linear contact with the side faces of said line of type, said bar being carried by said pallet substantially parallel to both of said surfaces by means of a supporting rod pivoted to said block at each end thereof, the free ends of said rods being rigidly fastened to said clamping bar at the opposite ends thereof, said bar being movable relative to said pallet toward and away from said first-named surface, and means for forcing the clamping edge of said clamping bar into clamping engagement with the side faces of said type lying parallel with said first-named surfaces.

2. A pallet for a stamping machine comprising a block adapted to support a line of type, said block having an elongated surface upon which the type is to be assembled and a surface extending at right angles from one edge of said elongated surface and upon which the end of said type is to rest, said pallet being open on the two sides facing said surfaces whereby said surfaces are freely accessible for the assembly of said type, an elongated clamping bar having a clamping edge, said clamping edge being adapted to provide a substantially linear contact with the side faces of said line of type, said bar being carried by said pallet substantially parallel to both of said surfaces by means of a supporting rod pivoted to said block at each end thereof, the free ends of said rods being rigidly fastened to said clamping bar at the opposite ends thereof, said bar being movable relative to said pallet toward and away from said first-named surface, and means for forcing the clamping edge of said clamping bar into clamping engagement with the side faces of said type lying parallel with said first-named surfaces.

45 HENRY A. MINTZ.
